ATTORNEYS

UNITED STATES PATENT OFFICE.

IGNATZ LOWY, OF CHICAGO, ILLINOIS.

LIQUID-DISPENSING APPARATUS.

1,372,968.

Specification of Letters Patent. Patented Mar. 29, 1921.

Application filed August 18, 1919. Serial No. 318,227.

To all whom it may concern:

Be it known that I, IGNATZ LOWY, a citizen of the United States, and a resident of the city of Chicago, in the county of Cook and State of Illinois, have invented a new and useful Improvement in Liquid-Dispensing Apparatus, of which the following is a full, clear, and exact description.

My invention relates to improvements in liquid dispensing apparatus, and it consists in the combinations, constructions and arrangements herein described and claimed.

An object of my invention is to provide a device, by means of which a liquid, such as a syrup or other similar liquid, may be readily discharged from a receptacle in a convenient and sanitary manner by the simple pressure of the finger against a releasing valve.

20 A further object of my invention is to provide a dispensing apparatus which contains a liquid under pressure, so that the latter may be forcibly discharged therefrom, as, for instance, when the device is to be used as means for charging soft drinks.

25 A further object of my invention is to provide a simple device which may be used in connection with any suitable retainer having a narrow neck, as, for instance, a glass bottle, means being provided for expanding resilient castings or washers so as to hold the dispensing mechanism readily in position, and at the same time to render the bottle air tight.

30 Other objects and advantages will appear in the following specification, and the novel features of the invention will be particularly pointed out in the appended claims.

35 My invention is illustrated in the accompanying drawing, forming part of this application, in which—

The figure is a central section through the device.

40 In carrying out my invention, I provide a body portion 1 of metal having an integral cylindrical portion 2, provided at its top with a threaded opening arranged to receive a screw cap 3. The cylindrical body portion is provided substantially midway between the ends with a shoulder 4, and is threaded at its lower end, both internally and externally. Arranged to enter the lower end of the body portion is a threaded end 5 of a pipe 6 which extends down to a point near

45 the bottom of the bottle or container 7. The

body portion is provided with a by-pass 8 which continues in an extension 9 leading to a valve casing 10 at the bottom of a pump or compressor 11. The valve casing 10 contains a valve 12 of any suitable form, which is designed to open to permit air to pass from the compressor 11 through the by-pass 8, and into the interior of the bottle 7, but will close immediately after the excess pressure on the top of the valve is relieved.

50 A piston valve 13 is disposed within the cylindrical portion 2 and is arranged to seat against the partition or flange 4. This valve is held normally against its seat by means of a spring 14, the lower end of which bears 60 on the end of the pipe connection 5. Surrounding the cylindrical body portion 2 is a plurality of washers or resilient rings 15. These rings are held between a nut 16 at one end and a nut 17 at the other, the nuts 16 and 17 being screwed to the outer surface of the cylindrical body portion. The nut 16 is provided with operating handles 18. The piston valve 13 is provided with a stem 19 which extends through the hollow body portion 75 and also through the screw cap 3. A spout 20 communicates with the interior of the cylindrical portion.

55 From the foregoing description of the various parts of the device, the operation 85 thereof may be readily understood. The portion containing the resilient washers or rings 15 is placed in the neck of the bottle 7, and then the nut 16 is forced downwardly by turning the handles 18, thus compressing 90 the rings and causing them to expand until they firmly engage the interior of the neck of the bottle 7, and thus make an air tight closure. It is assumed, of course, that prior to this any suitable liquid, such as syrup, 95 has been introduced into the bottle. With a few strokes of the handle 21 of the air compressor 11, the liquid is put under air pressure, but it cannot flow out, because the valve 13 is held closed by the spring. Now 100 on pressing down on a button or finger plate 22 at the top of the stem 19, the valve 13 may be forced from its seat, whereupon the pressure inside of the bottle will force the liquid up through the pipe 6, past the valve, 105 through the hollow body portion 2, and out at the spout 20. When the pressure is relieved, the valve instantly closes off the discharge passage.

110 The device may be used for dispensing

2

liquids of any kind, but is particularly desirable for use in dispensing syrups for soda water or the like. One can withdraw the exact amount desired by pressing downwardly on the button or plate 22 until the requisite quantity of liquid has been delivered, when the release of the button or plate 22 will cause the immediate cessation of the flow through the closing of the valve 13.

10 The device is simple in its nature, and may be made in many modified forms without departing from the spirit and scope of the invention.

I claim:

- 15 1. In a liquid dispensing device a receptacle, a tubular stopper therefor, said stopper having a hollow cylindrical body portion formed with an inwardly extending flange intermediate its length to form a valve seat, a piston valve disposed in the interior of the hollow body portion of said cylindrical stopper below said flange, a screw plug at the upper end of said cylindrical body portion, a valve stem arranged to pass through the screw plug and being connected with said valve, a spring arranged to bear against the under side of said valve to normally hold said valve against its seat, an intake pipe having a threaded end secured to the bottom of the tubular stopper, said pipe being arranged to extend into the receptacle, a plurality of superposed resilient rings surrounding a portion of the tubular stopper, a nut for supporting the rings, a second nut for compressing the rings against the first nut, whereby the rings are expanded to engage the wall of the mouth of the receptacle, an air compressor, means for establishing communication between the air

hollow cylindrical body portion of the tubular stopper.

2. In a liquid dispensing device a receptacle, a tubular stopper having a hollow cylindrical portion arranged to enter the mouth of the receptacle, said hollow cylindrical portion being provided with a valve seated on the interior thereof, a screw plug at the upper end of said hollow cylindrical body portion, a valve stem arranged to pass through the screw plug and being connected with said valve, a spring arranged to bear on said valve at one end, an intake pipe having a threaded end secured to the bottom of said stopper and communicating with said cylindrical body portion, said pipe being arranged to extend into the receptacle, a plurality of superposed resilient rings surrounding a portion of the tubular stopper arranged to enter the mouth of the receptacle, a nut for supporting the rings, a second nut for compressing the rings against the first nut, whereby the rings are expanded to engage the wall of the mouth of the receptacle, said tubular stopper being provided with a vertically extending passage in its wall opening into the interior of the receptacle, a laterally extending tubular extension formed integrally with said tubular stopper to communicate with said passage at the upper end thereof, an air compressor mounted on the outer end of said tubular extension and communicating therewith, whereby the flow of compressed air from said air compressor into the interior of said receptacle is permitted, and a spout connecting with said hollow cylindrical body portion of said tubular stopper at a point above the valve seated therein.

IGNATZ LOWY.
